UNITED STATES PATENT OFFICE.

JOHN CLULEE, OF WALLINGFORD, CONNECTICUT, ASSIGNOR TO THE SIMPSON NICKEL SILVER COMPANY, OF SAME PLACE.

DESIGN FOR A HANDLE FOR SPOONS, &c.

SPECIFICATION forming part of Design No. 26,627, dated February 16, 1897.

Application filed January 7, 1897. Serial No. 618,413. Term of patent 3½ years.

To all whom it may concern:

Be it known that I, JOHN CLULEE, of Wallingford, in the county of New Haven and State of Connecticut, have invented a new Design

5 for the Handles of Spoons, &c.; and I do hereby declare the following, when taken in connection with the accompanying drawings and the letters of reference marked thereon, to be a full, clear, and exact description of the same, and which said drawings constitute part of this specification, and represent, in—

10 Figure 1, a face view of a handle for spoons, &c., embodying my design; Fig. 2, a reverse view of the same.

15 This invention relates to a design for the handles of spoons, forks, and like articles of table-service; and the design consists in the configuration and ornamentation of the handle, as herein described and shown in the accompanying illustration.

20 As herein shown the design consists of a handle having at the juncture with the bowl a scroll-like ornamentation A, from which rises on either side a series B B of small pyramidal-shaped squares, gradually increasing in size toward the apex of the handle, where they meet a crowning scroll ornamentation C, and inclosing a slightly-convexed plain

panel D, surrounded by a rib, the upper portion of the panel overlapping upon the crowning scroll ornamentation and sharply defined therefrom.

25 The reverse side of the handle is ornamented by the scroll ornamentation A C, while the panel D is concaved, and the edges of the handle are outlined by simple elongated scrolls E E, coming together near the center of the handle and extending upward and downward to meet the scroll ornamentation A and C.

30 40 I claim—

1. The design for handles for spoons as herein shown and described.

2. In the design for handles of spoons and similar articles, the obverse, as herein shown 45 and described.

3. In the design for handles of spoons and similar articles, the reverse, as herein shown and described.

40 50 In testimony whereof I have signed this specification in the presence of two subscribing witnesses.

JOHN CLULEE.
